(57) **CLAIM**

The ornamental design for a board ball game, as shown and described.

DESCRIPTION

FIG. 1 is a top front right perspective view of a board ball game showing my new design;

FIG. 2 is a top rear left perspective view thereof;

FIG. 3 is a bottom front left view thereof;

FIG. 4 is a bottom rear right view thereof;

FIG. 5 is a front elevational view thereof;

FIG. 6 is a rear elevational view thereof;

FIG. 7 is a right elevational view thereof;

FIG. 8 is a left elevational view thereof;

FIG. 9 is a top plan view thereof;

FIG. 10 is a bottom plan view thereof; and,

FIG. 11 is a top, front, left perspective view of the board ball game in an alternate configuration.

The broken line showing of “hinges” is included for the purpose of illustrating portions of the “article” and forms no part of the claimed design.
